DESIGN FOR A COMBINATION TUMBLER CARRIER AND RACK

Henry J. Watral, Queens Village, N. Y.

Application May 11, 1940, Serial No. 92,309

Term of patent 3½ years

To all whom it may concern:

Be it known that I, Henry J. Watral, a citizen of the United States, residing at Queens Village, in the county of Queens and State of New York, have invented a new, original, and ornamental Design for a Combination Tumbler Carrier and Rack, of which the following is a specification, reference being had to the accompanying drawing, forming a part thereof.

In the drawing:

Fig. 1 is a front elevational view of a combination tumbler carrier and rack, showing my new design;

Fig. 2 is a top plan view, and
Fig. 3 is an end elevational view.

I claim:

The ornamental design for a combination tumbler carrier and rack, as shown.

HENRY J. WATRAL.
